UNITED STATES PATENT OFFICE.

FREDERICK H. SCHNEER, OF NEW ROCHELLE, NEW YORK.

BOY'S BLOUSE.

1,112,387.

Specification of Letters Patent.

Patented Sept. 29, 1914.

Application filed October 29, 1912. Serial No. 728,367.

To all whom it may concern:

Be it known that I, FREDERICK H. SCHNEER, a citizen of the United States of America, residing in New Rochelle, county 5 of Westchester, and State of New York, have invented certain new and useful Improvements in Boys' Blouses, of which the following is a specification.

This invention relates to an improved 10 boy's blouse in which the waistband of the same can readily adjust itself to the sizes of the waist of boys of different sizes and ages, without requiring a hemmed lower edge and a draw-string or band in the same; 15 and for this purpose the invention consists of a boy's blouse of the construction hereinafter described and finally pointed out in the claim.

In the accompanying drawing, Figure 1 20 represents a front-elevation of my improved boy's blouse, in which the front-corners are folded up so as to show the rear-portion of the waistband. Fig. 2 is a horizontal section on line 2, 2, Fig. 1, Fig. 3 is a 25 detail horizontal section showing the adjusting strap and its connection with the waistband of the blouse, on a larger scale, and Fig. 4 is a similar section of a modified form of the adjusting strap.

Similar letters of reference indicate corresponding parts throughout the different figures of the drawing.

Referring to the drawing, *a* represents a 30 boy's blouse, which is preferably made of the usual washable fabric. The bottom of the blouse is drawn in somewhat above the waistband *b* and closed in front by means of underlapping and overlapping portions having buttons and buttonholes. The rear- 35 part of the waistband *b* is provided with three buttonholes *b*¹ to which is applied an elastic waist-adjusting strap *d*, which is considerably shorter than the distance between the outermost buttonholes *b*¹ and provided 40 with three buttons *d*¹ that are inserted into the middle and outer buttonholes and form thereby folds.

The blouse is made in different sizes, so 45 that when the elastic strap *d* is applied to the waistband, each size can be made to fit

boys having different sizes of waist, as the elastic strap "gives" sufficiently so that the folds are stretched and the blouse and its waistband fit snugly around the waists. When the blouse is to be washed, the elastic 55 strap is detached, it being reapplied to the buttonholes on the waistband when the blouse is to be worn again.

For boys having smaller than the average sizes of waists, two auxiliary buttons *d*² are 60 added inside of the outermost button, as shown in Fig. 4, so that the blouse can also be snugly fitted to the waists of such boys. In place of buttons and buttonholes, means 65 operating in the same manner may be used. The advantages are that in washable blouses 70 the elastic draw-strings or bands are dispensed with, which, as they are washed with the garments, are soon useless, while the tying of the draw-strings and the unsightly dangling of their ends are dispensed with.

I have shown one embodiment of my invention, but it is clear that changes may be made therein without departing from the 75 spirit of the invention as defined in the appended claim.

I claim:

In a boy's blouse, the combination of a 80 waistband having button-holes in its rear-portion, a strap composed of elastic material only, and alongside the waistband, and provided with a button at the center thereof, and an outer button at each end of the strap, said buttons being adapted to be 85 passed through said button-holes correspondingly arranged, the elastic strap being shorter than the distance between the outer holes of the waistband for forming folds or plaits in the waistband over the buttons for 90 concealing the buttons when said waistband is folded.

In testimony, that I claim the foregoing as my invention, I have signed my name in presence of two subscribing witnesses.

FREDERICK H. SCHNEER.
